RAILWAY CAR DIAPHRAGM

John A. Wendland, Elkhart, Ind., assignor to
The Adlake Company, Chicago, Ill., a corpora-
tion of Illinois

Application October 24, 1945, Serial No. 624,188

4 Claims. (Cl. 105—18)

1

This invention has to do with railway car dia-
phragms of the so-called accordion type.

For many years it has been the practice to make
such diaphragms out of lubricated belting mate-
rial, the belting material being highly lubricated
in order to permit the folds and corners of the
diaphragms to bend and flex in various directions
without breaking down the threads in the mate-
rial. With the advent of more modern designs
in railway cars the necessarily dark and tarry
appearance of the diaphragms caused by the
presence of the lubricant has become objection-
able, with the result that attempts have been
made to improve the appearance of the dia-
phragms by giving them a silvery or other light
colored effect, by paint or plastic coatings, to
harmonize with the decorations of the car as a
whole. It has been found that such coatings do
not adhere satisfactorily to the surface for any
length of time, due to the oily character of the
lubricant, and attempts have therefore been made
to construct surface finished diaphragms from
lubricant-free fabrics. These attempts have not
been successful, owing to the rapid breakdown
of the fabric at the upper corners of the dia-
phragm where the fabric is ordinarily formed into
gussets or folds and the bending and flexing are
most pronounced.

The object of the present invention is to pro-
vide an improved diaphragm of the accordion
type in which the top and leg members are so
connected at the corners as to produce a free-
acting, weather-tight, wear-resisting structure
without the necessity of having the fabric from
which the members are made highly lubricated,
thus enabling the surface of the fabric to be left
either in its natural state or finished with any
desired decorative coating.

While the foregoing statements are indicative
in a general way of the nature of the invention,
other more specific objects and advantages will
be apparent to those skilled in the art upon a
full understanding of the construction of the
improved diaphragm.

A preferred embodiment of the invention is
presented herein by way of exemplification but
it will of course be appreciated that the invention
is susceptible of incorporation in other structur-
ally modified forms coming equally within the
scope of the appended claims.

In the accompanying drawings:

Fig. 1 is a face view of a single-fold diaphragm
constructed in accordance with the invention,
with the intermediate portions of the vertical leg
members broken away;

2

Fig. 2 is a plan view of one side of the dia-
phragm;

Fig. 3 is an edge view of the upper portion of
the diaphragm;

5 Fig. 4 is a fragmentary vertical section, taken
on the line 4—4 of Fig. 2;

Fig. 5 is another edge view of the upper por-
tion of the diaphragm, showing the latter in its
fully collapsed position;

10 Fig. 6 is a fragmentary vertical section, taken
on the line 6—6 of Fig. 5;

Fig. 7 is another edge view of the upper portion
of the diaphragm, showing the latter in its fully
extended position;

15 Fig. 8 is a fragmentary vertical section, taken
on the line 8—8 of Fig. 7;

Fig. 9 is a plan view of one of the soft pliant
corner pieces, before its application to the edges
of the top and leg members; and

20 Fig. 10 is an edge view of the upper portion
of a two-fold diaphragm, similarly constructed
in accordance with the invention.

Diaphragms of the accordion type are ordi-
narily of either single-fold or two-fold construc-
25 tion.

While the present invention is equally ap-
plicable to either construction, a single-fold dia-
phragm is shown in Figs. 1 to 9, inclusive, for
simplicity of illustration. This diaphragm, like

30 other diaphragms of the accordion type, is adapt-
ed to be positioned between and secured to the
end of the car and the face plate, whereby to
form a closed passageway from the vestibule of
one car into the vestibule of the next.

As will be observed in Figs. 1 to 9, inclusive,
35 the diaphragm consists of separate top and leg
channel members 10 and 11 which are construct-
ed of thick longitudinally stiff fabric, preferably
three-ply belting material. These members are
of outwardly opening generally U-shaped cross

40 section with reference to the passage through the
diaphragm and are contractible and extensible
in a direction at right angles to their lengths.
The top member 10 is disposed in a generally
horizontal position and the ends 12 of the top

45 member are arranged within the contour of the
upper ends 13 of the leg members. The upper
ends 13 of the leg members are centrally cut
away to provide recesses 14 of upwardly opening
generally U-shaped form for the free reception

50 of the ends 12 of the top member.

At the upper corners of the diaphragm the ends
12 of the top member are connected with the ends
13 of the leg members by means of free acting
corner pieces 15 of relatively thin, soft, pliant
55 material. Chrome leather has been found ex-

cellent for this purpose. The corner pieces 15 are of generally L-shaped form, as shown in Fig. 9, and are sewed or otherwise secured along their reentrant edges 16 to the edges 17 of the ends of the top member and along their opposed edges 18 to the edges 19 of the U-shaped recesses in the upper ends of the leg members. The corner pieces 15 are loosely sleeved back under the ends 12 of the top member in variably divergent relation thereto, the positions assumed by the corner pieces with respect to the ends of the top and leg members depending upon the degree of contraction or extension of the diaphragm. In an extremely contracted position, such as shown in Figs. 5 and 6, the corner pieces 15 will be so disposed as to more or less snugly conform to the convex surface of the top member 10, whereas in an extremely expanded position of the diaphragm, such as shown in Figs. 7 and 8, the corner pieces 15 will diverge more or less abruptly from the convex surface of the top member.

In order to obtain a nicely tailored fit of the corner pieces 15 to the edges of the top and leg members some additional fullness is desirable in the corner pieces at 20, along their edges 18. This added fullness may be obtained without difficulty by cutting each of the corner pieces in two identical sections 21 and providing them with edges 22 which are adapted to be overlapped and sewn together at 23 in generally parallel relation. The edges 22 are initially cut with an outward curve at 24 and thereafter sewed together in a more or less straight line, whereby to produce the desired fullness at 20.

Fig. 10 shows a two-fold, as distinguished from single-fold, diaphragm constructed in accordance with the invention. In this diaphragm two sets of top and leg members 10 and 11, similarly joined by corner pieces 15, are employed.

The improved diaphragm is adapted to effectively withstand the folding, creasing, buckling and twisting to which diaphragms are constantly subjected in modern high speed railway operation, and will give satisfactory service over a long period of time because of the freely yieldable nature of the novel corner connections, which connections readily conform to the expansion and contraction of the diaphragm at the corner locations, without undue strains or stresses.

I claim:

1. In a railway car diaphragm of the accordion type, separate top and leg channel members of flexible sheet material, which members are of outwardly opening cross section and are collapsible and extensible in a direction at right angles to their lengths, the ends of the top member extending laterally into the upper ends of the leg members, and the upper ends of the leg members being centrally relieved to provide upwardly opening recesses for the free reception of the ends of the top member, and corner pieces of relatively thin soft pliant material which are secured along

certain of their edges to the edges of the ends of the top member and along their remaining edges to the edges of the recesses in the upper ends of the leg members, with the corner pieces loosely sleeved back under the ends of the top member in variably divergent relation thereto depending upon the degree to which the diaphragm is collapsed or extended.

10 2. In a railway car diaphragm of the accordion type, separate top and leg channel members of thick longitudinally stiff fabric, which members are of outwardly opening generally U-shaped cross section and are collapsible and extensible in a direction at right angles to their lengths, the ends of the top member extending laterally into the upper ends of the leg members, and the upper ends of the leg members being centrally relieved to provide recesses of upwardly opening generally U-shaped form for the free reception of the ends of the top member, and corner pieces of relatively thin soft pliant material of generally L-shaped form which are secured along their reentrant edges to the edges of the ends of the top member and along their opposed edges to the edges of the U-shaped recesses in the upper ends of the leg members, with the corner pieces loosely sleeved back under the ends of the top member in variably divergent relation thereto depending upon the degree to which the diaphragm is collapsed or extended.

20 3. In a railway car diaphragm of the accordion type, separate top and leg channel members of thick longitudinally stiff multi-ply fabric, which members are of outwardly opening generally U-shaped cross section and are collapsible and extensible in a direction at right angles to their lengths, the ends of the top member extending laterally into the upper ends of the leg members, and the upper ends of the leg members being centrally relieved to provide recesses of upwardly opening generally U-shaped form for the free reception of the ends of the top member, and corner pieces of relatively thin soft pliant leather of generally L-shaped form which are secured along their reentrant edges to the edges of the ends of the top member and along their opposed edges to the edges of the U-shaped recesses in the upper ends of the leg members, with the corner pieces loosely sleeved back under the ends of the top member in variably divergent relation thereto depending upon the degree to which the diaphragm is collapsed or extended.

40 4. A railway car diaphragm of the construction set forth in claim 1, in which said corner pieces are members of generally L-shaped form which are composed of a plurality of initially flat pieces of material, which pieces are joined together in such manner as to produce in the corner pieces additional fullness along the center portions of the outer edges of the latter.

JOHN A. WENDLAND.
